UNITED STATES PATENT OFFICE

FRAZER CHRISTIE, OF PHILADELPHIA, PENNSYLVANIA, ASSIGNOR TO COFFIN AND ALTEMUS, OF SAME PLACE.

DESIGN FOR A PRINTED FABRIC.

Specification forming part of Design No. 5,505, dated February 6, 1872.

Specification describing a Design for a Printed Fabric, produced or invented by FRAZER CHRISTIE, formerly of Glasgow, Scotland, but now residing in Philadelphia, Pennsylvania.

The nature of my design is fully represented in the accompanying photographic illustration, to which reference is made, and in which—

Figures 1, 2, 3, and 4 represent different modifications of the design.

The main peculiarity of the design consists of stripes of what I term a frosted pattern, alternating with stripes the character of which is immaterial. Thus in Fig. 1 there is a stripe, A, having a frosted pattern interposed between two stripes, D D.

I apply the term frosted to the main stripes of the fabric because the pattern is derived from the appearance of frost, as, for instance, the frozen surface of a sheet of glass, which, on occasions, presents a complicated system of foliated ornamentation, differing in detail, but

having the same general character throughout. The frosted stripe D in Fig. 2 differs from that in Fig. 1, and the frosted stripe E in Fig. 3 and that in Fig. 4 differ from each other, as well as from the stripes in Figs. 1 and 2; but although the patterns of the stripes differ in detail they present the same generic appearance of complete foliated scrolls.

Irrespective of the colors employed,
I claim—

A design for a fabric consisting of parallel stripes and intermediate frost-like surface, as set forth.

In testimony whereof I have signed my name to this specification in the presence of two subscribing witnesses.

FRAZER CHRISTIE.

Witnesses:

WM. A. STEEL,
HARRY SMITH.
